[57] CLAIM

The ornamental design for a handle, as shown and described.

DESCRIPTION

FIG. 1 is a left/top/front isometric view of a handle of our new design shown in an upright position, it being understood that the carrying case shown in broken lines is for illustrative purposes only and forms no part of the claimed design; FIG. 2 is a left/top/rear isometric view of the handle shown in a folded position thereof; FIG. 3 is an enlarged front elevational view thereof; FIG. 4 is an enlarged rear elevational view thereof; FIG. 5 is an enlarged top plan view thereof; FIG. 6 is an enlarged bottom plan view thereof; FIG. 7 is an enlarged left side view thereof; FIG. 8 is an enlarged right side view thereof; and, FIG. 9 is an enlarged left side cross-sectional elevational view taken along line "9—9" of FIG. 3 thereto.
